(57) **CLAIM**

The ornamental design for a frame for an electric bicycle, as shown and described.

DESCRIPTION

FIG. 1 is a top, front, and right-side perspective view of a frame for an electric bicycle embodying our new design; FIG. 2 is a front elevation view thereof; FIG. 3 is a rear elevation view thereof;

FIG. 4 is a right-side elevation view thereof;

FIG. 5 is a left-side elevation view thereof;

FIG. 6 is a top plan view thereof; and,

FIG. 7 is a bottom plan view thereof.

The broken line showing of various portions of a frame for an electric bicycle are provided for the purposes of illustrating environmental structure and form no part of the claimed design.

1 Claim, 7 Drawing Sheets
